(57) **CLAIM**

The ornamental design for a vehicle interface device, as shown and described.

DESCRIPTION

FIG. 1 is a rear perspective view of a vehicle interface device showing the design in an environmental use;

FIG. 2 is a rear perspective view of the vehicle interface device of FIG. 1;

FIG. 3 is a front perspective view of the vehicle interface device of FIG. 1;

FIG. 4 is a top view of the vehicle interface device of FIG. 1;

FIG. 5 is a bottom view of the vehicle interface device of FIG. 1;

FIG. 6 is a left side view of the vehicle interface device of FIG. 1;

FIG. 7 is a right side view of the vehicle interface device of FIG. 1;

FIG. 8 is a front view of the vehicle interface device of FIG. 1; and,

FIG. 9 is a rear view of the vehicle interface device of FIG. 1.

The broken lines in the drawings are for the purpose of illustrating portions of the vehicle interface device that form no part of the claimed design.
